UNITED STATES PATENT OFFICE.

HORATIO G. GILLMOR, OF QUINCY, MASSACHUSETTS, ASSIGNOR TO NEW JERSEY DEVELOPMENT COMPANY, OF NEW YORK, N. Y., A CORPORATION OF NEW JERSEY.

AUTOMOBILE TORPEDO.

980,243.

Specification of Letters Patent. Patented Jan. 3, 1911.

Application filed October 28, 1907. Serial No. 399,517.

To all whom it may concern:

Be it known that I, HORATIO G. GILLMOR, a citizen of the United States of America, residing at Quincy, county of Norfolk, State of Massachusetts, have invented a new and useful Improvement in Automobile Torpedoes, of which the following is a specification, accompanied by drawings.

My invention relates to torpedoes, and more particularly to that class of torpedoes known in the art as "automobile" torpedoes, and one of the objects of my invention is to construct a torpedo which for a given size and weight shall be capable of traveling at a greater speed and for a greater distance than is the case with torpedoes as heretofore constructed.

Another object is to minimize change in moment of weight of the torpedo about the center of buoyancy thereof, as the working fluid escapes in running; and so to obviate the need for maintaining the diving rudders at an increasing angle toward the end of the run of torpedo, thereby avoiding the resistance introduced by the maintenance of these rudders at an angle.

Another object is to avoid the loss of heat to the water in which the torpedo moves, which loss of heat seriously reduces the efficiency of torpedoes in which the air is preheated by burning the combustible within the air flask of such torpedoes.

Further objects of the invention will hereinafter appear; and, to these ends, the invention consists of a torpedo for carrying out the above objects embodying the features of construction, combination of elements, and arrangement of parts having the general mode of operation substantially as hereinafter described and claimed in this specification and shown in the accompanying drawings; in which—

Figure 1 is a longitudinal vertical section of a torpedo embodying my invention, parts at front and rear of the same being broken away. Fig. 2 is a section at the plane indicated by $\alpha\alpha$ in Fig. 1 looking toward the forward end of the torpedo with the boiler flues showing through the water. Fig. 3 is a section at the plane indicated by $\gamma\gamma$ in Fig. 1.

Similar letters refer to similar parts throughout the several figures.

(a) represents the flask in which compressed air at high pressure is carried, and

(b) a vessel constructed to stand within the air flask (a), and provided with a vapor and liquid space (c) and a combustion space (d).

(e) represents the propelling motor for the torpedo; (f) a pump driven by the propelling motor drawing water, from the water in which the torpedo moves, by the inlet pipe (g); and discharging the same through pipe (h) to the space (c) of the vessel (b); and (i) a fuel pump also driven by the propelling motor drawing liquid fuel through the suction pipe (k) from the fuel tank (l), and discharging the same through the discharge pipe (m) to the combustion space (d) of the vessel (b).

(n) represents an outer casing separated from the lower portion of the vessel (b) by spaces (o) forming passages by which air may pass to the duct (p) and thence to the free-surfaces of the liquid (q) in the combustion space (d).

(r) is a water space formed by double walls of the vessel (b) at the top thereof; into which space the water is discharged by the pump (f) through the pipe (h). The space (r) is kept full by the dam or baffle plate (s) over the top of which the water must flow to reach the main water space (c) of the vessel (b).

(t) represents flues by which the gases pass from the combustion space (d) to the space (c), and (u) a tube communicating with the main supply pipe (v) supplying motive fluid to the motor.

(w) represents an igniting or primer tube for igniting the combustible (q) at the proper moment, and (z) supports for retaining the vessel (b) in place within the air flask (a).

The weight of air carried in the flask of a torpedo is capable of burning more than one sixth its weight of a hydrocarbon such as alcohol. As now constructed only a limited amount of such hydrocarbon is burned by the air charge to raise the temperature of the air before entering the propelling motor and so increase the work done by it. A limit to the amount of heat which may be so added is placed by the necessity of limiting the temperature of the working fluid to a temperature which may be withstood by the materials of which the motor is constructed, and, in any case, the amount of hydrocarbon so burned is very much less than that which might be burned by the air

contained in the air flask. Furthermore, when the hydrocarbon is burned within the air flask, even the burning of this limited quantity of fuel involves great loss of heat 5 through the walls of the flask to the external water, with a corresponding serious reduction in efficiency.

The rate of combustion of a fuel in air under pressure increases rapidly with increase of pressure of the air within which 10 the fuel burns. So rapid is this increase in rate that, for equal surfaces of fuel, the rate in air at one thousand pounds pressure is nearly twenty-five times that in air at atmospheric pressure. This increase in combustion rate at high pressure makes it possible to provide, within a small space and 15 without special means, for the burning in a short time of a relatively large weight of fuel for the generation of heat.

One feature of this invention resides in the employment of the air provided primarily for the propelling charge of a torpedo to burn a quantity of fuel, preferably 20 in liquid form, approximating to the full quantity which can be burned by the air charge and the utilization of the heat so produced for the propulsion of the torpedo by generating under pressure the vapor of 25 a liquid; which vapor, together with the products of combustion, at a temperature as high as practicable, are employed to drive the propelling motor of the torpedo. To accomplish this I construct the torpedo with 30 a vessel (b), which is virtually a boiler open freely on the vapor side of the air within which the fuel for firing the boiler is burned. Since the pressure is equal on all sides of the 35 material of this vessel, the sheets of which it is constructed need be only of the thickness necessary for reasonable rigidity and to contain the fluids used. The boiler may, 40 therefore, be of very light construction. To avoid possible injurious effect of large free 45 surfaces of fluid upon the longitudinal and transverse stability of the torpedo, the water spaces in the vessel (b) are sub-divided by longitudinal and transverse partitions having small apertures to permit the fluid to 50 flow slowly from one side to the other to equalize levels but prevent sudden rush of fluid such as might be occasioned by giving 55 an inclination to the torpedo in any direction. These partitions serve further to add to the stiffness of the light construction of the vessel.

To insure the presence of fuel in the space (d) at starting a small quantity is let into 60 the combustion space (d) of the vessel (b) before charging the air flask. When the torpedo is charged the pressure on the surface of (g) will close the discharge valve of the pump (i) and further flow of the 65 fuel from the fuel tank (l) to the space (d) will be prevented until the starting of the

motor (e). The fuel tank (l) is preferably completely filled after the torpedo is charged. Launching the torpedo sets the pump (i) in motion; after which a definite amount of fuel will be discharged at (g) by each stroke 70 of the pump.

I construct the combustion space (d) with greatly flaring sides so that a shallow vessel is formed in which the area of the free surface of liquid will, with only a small increase in the depth of the liquid increase from the area of the cylindrical bottom part to many times that area. The area of the cylindrical bottom part is arranged to give the desired rate of combustion of the fuel 80 in air at the high pressure with which the torpedo starts. The range in area of the free surface of liquid to be provided for in the combustion space (d) will vary with the designed initial and final air pressure in the 85 flask and depends upon these pressures. For example, if the initial and final pressures were designed to be 1,000 pounds and 300 pounds per square inch, respectively, the combustion space would be designed so that 90 a small increase in depth of the liquid would increase the area of the free surface of the liquid fuel exposed to the air from the area of the cylindrical bottom part to about 24 times that area, or if the initial and final 95 pressures were 2,000 pounds and 300 pounds per square inch, respectively, an increase of about seven times in the free surface area of the liquid would be provided for. In this way provision is made for an almost 100 constant rate of burning for the range in flask pressure from the beginning to the end of the run of the torpedo.

The fuel (q) is ignited at the proper moment by means of a primer or ignition tube similar to that heretofore employed for the ignition of liquid hydrocarbon for heating the air within the flask of torpedoes. To avoid the loss of heat which would result from general heating of the air contained within the air flask, the walls of the combustion space of the vessel (b) are made double as illustrated, and form between them spaces (o) which provide passages; through which the air, following the course 110 indicated in the drawing by the arrows reaches the free surfaces of the liquid at (g), taking up on its way heat which would otherwise be radiated to the general air content of the flask.

The pump (f) set in motion by the motor (e) when the torpedo is launched, will draw water from the sea through the inlet pipe (g), and discharge the same through the discharge pipe (h) to the space (r) of the vessel (b), and thence to the steam and water space (c) thereof. The construction of the vessel (b) with double walls at its top, in the manner indicated 115 serves a double purpose preventing loss of 120

heat from the top of the vessel to the general content of the air flask and thence through the walls of the torpedo to the surrounding water; and at the same time, increases greatly the heating surface of the boiler. The water discharged into the vessel follows the course indicated in the drawing by the arrows; and is, therefore, first presented to contact with gases after they have been 10 already considerably cooled. It is possible by this construction to provide relatively great heating surfaces with a boiler having small water content. The vapor generated by the heating of the water in the vessel (b) 15 mixes with the products of combustion in the space (c) after these have traversed considerable heating surfaces and their temperatures have been reduced. The admixture of the vapor with the products of combustion further reduces the temperature of the whole; and, at this high but limited temperature, the products of combustion, air and vapor are led by the pipe (u) which, since it bears no pressure, may be very light 20 in construction, to the supply pipe (v) and thence to the main propelling motor of the torpedo.

Since the total heat of evaporation of water falls with reduction in the pressure, 30 the weight of water evaporated by the heat of combustion of the constant supply of fuel will be less at high pressures than at low pressures; and, therefore, as the pressure within the flask falls there will be an increase in the rate of evaporation. This increase in evaporation rate with falling pressure will tend to reduce the rate of fall of pressure within the flask. I prefer to construct the pumps (f) and (i) opposite 40 one another with plungers driven at the same speed with the same stroke and to give to the two plungers such sectional areas that the volumes displaced by them are in the ratio of the volume of water to the volume 45 of liquid hydrocarbon necessary for its evaporation under the average conditions as to initial temperature of the water and pressure within the flask (a). By so constructing the pump there will be delivered 50 to the vessel (b) with each unit weight of water the necessary weight of fuel to insure the evaporation of this water.

The withdrawal of mixed vapor and products of combustion from the space (c) 55 through the duct (u) to the motor, through the supply pipe (v), introduces air through the spaces (o) and the pipe (p) to the combustion space (d) and keeps a continuous supply of the necessary air for the combustion of the fuel at (q) within this space. The mixed vapor and products of combustion at the temperature at which they are led to the motor, are of much greater volume than, and are capable of doing work 60 greatly in excess of the work which could

be done by, the air which was employed for the burning of the fuel, used in the ordinary way. With a given air content for the flask, therefore, the speed or the distance run or both may be greatly increased by constructing the torpedo in accordance with this invention. 70

In torpedoes as now constructed the weight of air with which the flask is charged is a considerable percentage of the displacement of the torpedo and this weight has its center of gravity at a distance from and forward of the center of buoyancy of the torpedo. The escape of this air through the propelling motor lightens the torpedo 75 when running; and, since the weight removed is forward of the center of buoyancy, changes the balance of the torpedo and causes the bow to tend to rise. To keep the torpedo at the proper depth this tendency of the bow to rise has to be corrected 80 by the diving rudders and to maintain these at the necessary angle increases the resistance opposing the passage of the torpedo through the water and reduces its speed. 85 To avoid this change in balance, I arrange the tank containing the fuel carried so that the distance of the center of gravity of the fuel from the center of buoyancy on one side shall be, as near as may be, as many 90 times the distance of the center of gravity of the air in the air flask from the center of buoyancy on the other side as the weight of air discharged in running the torpedo for a given interval of time is a multiple of the 95 weight of fuel withdrawn from the tank for burning during the same time. For example, if it be arranged that alcohol is employed as a fuel and that nearly but not quite all the alcohol which could be burned 100 by the air discharged, leaving some unconsumed air, is supplied, the weight of air discharged would be about seven times the weight of alcohol withdrawn from the tank 105 and burned. The air flask and fuel tank 110 would in this case be so placed that the distance of the center of gravity of the fuel, aft, or to the rear, of the center of buoyancy of the torpedo would be about seven times the distance of the center of gravity of the 115 air contained in the flask forward of the center of buoyancy of the torpedo. The tendency of the bow to rise on account of the discharge of air would then be counteracted by the withdrawal and burning of 120 one seventh the weight of this air in fuel from the fuel tank at a distance aft of the center of buoyancy seven times the distance that the center of gravity of the air discharged is forward of the center of buoyancy; and, since the ratio of air discharged 125 to fuel burned is approximately constant, an approximately unchanged total moment of the weight of the torpedo and its contents about the center of buoyancy of the torpedo 130

will be maintained throughout the run of the torpedo and the loss of speed incident to the use of the diving rudders to correct changing balance of the torpedo will be 5 avoided, with a corresponding increase in range and accuracy of the torpedo.

It will be understood that the vapor generator might be installed external to the air flask (a) and the air, after discharge from 10 the flask, be employed for burning the fuel and generating a vapor under pressure, which vapor would be mixed with the products of combustion and the mixture employed in the propelling motor. Such an 15 arrangement while possible is open to the objection that considerable space would be required, and also considerable additional weight on account of the necessity of constructing all parts to withstand the pressure 20 (usually 350 to 500 lbs.) at which the motive fluid is supplied to the motor. The liquid for evaporation might also be stored within the hull of the torpedo with suitable 25 means for its supply to the vapor generator instead of employing, for the purpose, water drawn from the sea. It will be understood also that in place of a liquid fuel there might be employed a gaseous fuel contained 30 under pressure in a fuel tank with suitable means to control the flow thereof from the gaseous fuel tank to the combustion chamber (d); and further, that, instead of the means shown for producing and 35 regulating the supply of fuel to the combustion space, other means such for instance as the pressure of gases on the surface of the liquid fuel might be employed to produce the flow thereof.

Obviously some features of the invention 40 may be used without others, and the invention may be embodied in widely varying forms. Therefore, without limiting the invention to the construction shown or described or enumerating equivalents, I claim 45 and desire to secure by Letters Patent the following:—

1. An automobile torpedo, including, in combination with a compressed air flask a shallow vessel adapted to hold liquid fuel 50 with its free level surface exposed to the air in said air flask, the sides of said vessel being constructed with such flare that small increments in the depth of the liquid fuel in said vessel so increase the area of the exposed surface thereof as to automatically 55 adjust the rate of burning of said fuel to falling pressures of the air within said flask, means for supplying liquid fuel to said vessel at an approximately constant rate and 60 means whereby said fuel may be ignited.

2. An automobile torpedo, including, in combination with a compressed air storage reservoir, a completely inclosed combustion chamber wholly contained within said reservoir, means whereby the heat radiated

from the walls of said combustion chamber is intercepted and employed to heat the air passing to said combustion chamber, means for supplying fuel to said combustion chamber and means whereby hot gases may be led 70 from the interior of said combustion chamber to the propelling motor of said torpedo, substantially as described.

3. The combination in an automobile torpedo, of a boiler constructed to contain a 75 vaporizable liquid and the vapor thereof and provided with a combustion chamber separated from the liquid contained by said boiler by heat conducting walls, with an air storage reservoir, a fuel tank and means for 80 supplying and burning fuel and air in the combustion chamber of said boiler, substantially as described.

4. An automobile torpedo, including, in combination with an air storage reservoir, a 85 boiler wholly contained within said reservoir, constructed to hold a vaporizable liquid and the vapor thereof, means for supplying a vaporizable liquid to said boiler, a fuel storage tank, and means whereby fuel 90 may be supplied and burned under said boiler within said air storage reservoir, substantially as described.

5. A self-propelled torpedo provided with a compressed air flask, a fuel storage 95 tank, a boiler constructed with water and steam spaces and a separate combustion chamber, means for supplying water to said boiler, means for supplying and burning fuel in the combustion chamber of said 100 boiler, and means for mixing the vapor generated in said boiler with the gases of combustion after said gases have traversed heating surfaces of said boiler, whereby the volume of fluid under pressure and the 105 energy supplied to the propelling motor of said torpedo are greatly increased.

6. An automobile torpedo having a reservoir containing compressed air, a boiler constructed with combustion spaces separated 110 by suitable heat-transmitting walls from the water spaces to said boiler, means for supplying water to said boiler, a fuel containing tank, means for supplying, igniting and burning fuel in the combustion spaces of 115 said boiler, means for mixing steam generated in said boiler with gases of combustion after said gases have been cooled by contact with water-cooled surfaces of said boiler, and a pipe to conduct vapor and 120 gases under pressure from said boiler to the motor propelling said torpedo, substantially as described.

7. A self-propelled torpedo provided with a compressed air flask, a boiler within said 125 flask, constructed with vapor and liquid spaces and separate combustion spaces, means whereby a vaporizable liquid and a suitable quantity of fuel to evaporate the same are supplied to the vapor and liquid 130

spaces and to the combustion spaces, respectively, of said boiler, means whereby admixture of the vapor and products of combustion are effected, and means whereby mixed vapor and gases are led to the motor of said torpedo.

8. A self-propelled torpedo including, in combination with an air storage reservoir, a boiler constructed with water and vapor spaces and a separate combustion chamber divided from the water space by heat conducting walls, in contact at one side with the water within said boiler, a pump for supplying water from the sea to said boiler, a fuel-containing reservoir, means for supplying, igniting and burning fuel in the combustion chamber of said boiler, and means whereby steam and gases under pressure are supplied to the propelling motor of said torpedo, substantially as described.

9. The combination of a compressed air storage reservoir with a boiler constructed to be wholly contained within said reservoir, means for supplying water to said boiler, and means for supplying fuel to be burned within the air under pressure in said reservoir for the generation of steam in said boiler.

10. An automobile torpedo, including, in combination with a compressed air storage reservoir, a slightly constructed boiler contained within said reservoir open to the gases therein and arranged to hold a vaporizable liquid, the vapor thereof and gases, means for supplying a vaporizable liquid to said boiler, and means for supplying and burning a fuel under said boiler, substantially as described.

11. An automobile torpedo including, in combination with a compressed air storage reservoir, an inclosed vessel wholly contained within said storage reservoir constructed with spaces to contain a vaporizable liquid and the vapor thereof, and separate combustion spaces, means for supplying a vaporizable liquid to said vessel, and

means for supplying and igniting fuel in the combustion spaces of said vessel, substantially as described.

12. An automobile torpedo, including, in combination with a compressed gas storage reservoir having its center of gravity at one side of the center of buoyancy of the torpedo, a liquid storage reservoir having its center of gravity at the other side of the said center of buoyancy, connections for withdrawing the stored gas from its reservoir for the propulsion of the torpedo, and means for simultaneously withdrawing the stored liquid from its reservoir in such amount that the weight of the gas withdrawn multiplied by the distance of its center of gravity to one side of the center of buoyancy is equal to the weight of the liquid withdrawn multiplied by the distance of its center of gravity to the other side of the center of buoyancy, whereby the balance of the torpedo is maintained.

13. The combination in an automobile torpedo of a storage reservoir for an oxygen carrier, a storage reservoir for fuel, a combustion chamber, connections for supplying the oxygen carrier and fuel to the combustion chamber, and means for igniting them therein, the oxygen-carrier reservoir and the fuel reservoir being so placed on opposite sides of the center of buoyancy of the torpedo that the weight of the oxygen-carrier consumed multiplied by the distance of its center of gravity to one side of the center of buoyancy is equal to the weight of fuel consumed multiplied by the distance of its center of gravity to the other side of the center of buoyancy, whereby the balance of the torpedo is maintained.

In testimony whereof I have signed this specification in the presence of two subscribing witnesses.
